UNITED STATES PATENT OFFICE.

FRED SCHOENWOLF, OF CHICAGO, ILLINOIS, ASSIGNOR, BY MESNE ASSIGNMENTS, TO
CURTIS B. CAMP, TRUSTEE, OF OAK PARK, ILLINOIS.

CARBURETOR.

Application filed October 14, 1922. Serial No. 594,521.

This invention relates to carburetors for lifting fuel from a low level supply to a position adjacent to an internal combustion engine, and there mixing the fuel with air 5 to form a combustible mixture.

The carburetor of my invention utilizes a small Venturi tube acting to enhance the suction of the carburetor mixing chamber for fuel lifting purposes. The advantages 10 gained from carburetors having means for enhancing the mixing chamber suction for lifting fuel to a float chamber, or other reservoir, are fully set forth in the patent to Milford G. Chandler, No. 1,870,949, dated 15 March 8, 1921, and need not be repeated here.

My carburetor is primarily intended for use upon an automobile, and one object of the invention is to simplify and lighten the 20 structure of carburetors used for this purpose so that there will be few parts liable to become disordered through vibration and wear.

Another object of the invention is to provide a construction in the manufacture of which considerable tolerance of dimensions may be allowed without interfering with the 25 successful operation of the device. The invention comprises, primarily, a movable sleeve shaped internally like the discharge end of a Venturi tube, this sleeve serving both for providing a variable restriction to the admission of air to the mixing chamber of the carburetor, and for creating a velocity 30 suction upon the discharge end of a primary nozzle Venturi tube which acts to withdraw fuel from the carburetor float chamber or reservoir, the movable sleeve further serving in its movement to control 35 the size of the discharge opening into the mixing chamber from a vacuum Venturi tube used for creating an enhanced suction in the upper spaces of the carburetor float chamber or fuel reservoir.

40 My invention is illustrated in the accompanying drawing, in which

Figure 1 is a vertical section, and

Figure 2 is an elevation partly broken away taken 90° from that of Figure 1.

45 Referring to the drawing, in which like parts are designated by like reference characters, the main housing 3 is attached to the intake manifold of an internal combustion engine, (not shown) by means of a flange 50 4 provided in the usual manner with bolt

or screw holes. The housing 3 is preferably of cast metal, shaped as illustrated to provide a secondary intake opening 5, and discharge opening 6. A sleeve 7 is preferably fitted within the opening 6 to provide a 60 spring seat 8 for the spring 9, which normally holds the movable tube 10 in contact with the seat 11, thus cutting off the passage between the intake opening 5 and the discharge opening 6. Within the discharge 65 opening 6 is the usual throttle 12, controlled by the lever 13 in the usual manner. The seat 11 is centrally bored to receive the discharge end of a nozzle Venturi tube 15, which extends about one-fourth of an inch 70 above the face of the seat 11 along the axis of the movable tube 10. Atmosphere is conducted to the external end of the nozzle Venturi tube 15 through a downwardly extending tubular portion 17 forming a part 75 of the main casting 3, and also serving as a means for holding the float chamber bowl 18 in place. Fuel is conducted to the nozzle openings 19 within the Venturi tube 15 through a duct 20, shown in Figure 2. A 80 float 21 controls a float valve 22, so as to admit fuel only when the fuel in the float chamber falls below a predetermined level.

A vacuum Venturi tube 25 extends through the housing 4 at substantially right angles 85 to the bore of the passage 6, and terminates in the mixing chamber at a position substantially on the line of the upper edge of the movable tube 10 when that tube is in its normal position. The external surface of 90 the movable tube 10 is contoured at 26, so that for different positions of the tube 10 along its axis it will serve to variably restrict the discharge end of the vacuum Venturi tube 25. This vacuum Venturi tube has 95 a very small throat, so that the air admitted through it will be much less than that necessary for the smallest engine demand. The tube 25 preferably has a pressed fit within the housing 3, and has openings 27 which 100 communicate by means of a passage 28 with the upper space of the float chamber. A cam 30, pivoted at 31 and held against a flat surface on the housing 3 by means of a spring washer 32, is so shaped that by its 105 rotation the entrance to the Venturi tube 25 may be variably restricted, or even entirely closed. When this cam is rotated to a position in which the Venturi tube 25 is entirely closed, an opening 34 through the cam 110

registers with a passageway 35 in the housing which leads to the space surrounding the movable tube 10. The purpose of this is to relieve the vacuum within the space surrounding the tube 10, so that suction within the discharge opening 6 will have less effect in raising the tube 10 off its seat 11, and thus cause a higher suction to be created in the mixing chamber of the carburetor for enriching the mixture in starting.

A mixture of fuel and air for idling purposes is conveyed from a position near the discharge end of the nozzle Venturi tube 15 to a point on the engine side of the throttle 12 through a drilled passageway 40, in which is located an adjusting screw 41 by means of which the effective size of the passageway may be altered. A low level supply tank 43 is shown partially in section in Figure 2, it being understood that this tank will, in practice be located at some distance away from the carburetor, and will usually be located at the rear of the vehicle when the carburetor is used in connection with an automobile engine.

In the operation of the device, because of the ample clearance between the sleeve 7 and the movable tube 10, the suction of the engine will be effective within the chamber in which the spring 9 is located, and will, under normal conditions of operation, raise the movable tube 10 slightly off its seat 11 to admit a small amount of air between the lower edge of the tube and its seat, the opening through the nozzle 15 being so small that the air and fuel admitted at this point will not supply the engine even for its lowest idling demand. The suction within the mixing chamber under the lowest demand of the engine will, of course, be controlled by the strength of the spring 9, and the weight of the movable tube 10. These are preferably adjusted so that a suction equivalent to about 15 inches of gasoline in a manometer tube is required for lifting the tube 10 off its seat 11. The vacuum Venturi tube 25 serves to enhance this suction, so that even for the idling condition of the motor the suction available at the throat of the vacuum Venturi tube is equivalent to about 40 inches of gasoline in a manometer tube. This suction is available for lifting fuel from the low level supply to the carburetor reservoir. Notwithstanding this high suction in the fuel reservoir, the nozzle Venturi tube 15 will withdraw fuel from the reservoir. This is because the discharge end of the nozzle Venturi tube 15 is located within the reciprocating tube 10 at a point where the velocity of the air is made high by its passing around the enlargement 11 and through the restricted intake end of the tube 10. This increased suction at the discharge end of the nozzle Venturi tube correspondingly increases the suction at the fuel inlet openings,

which suction by the design of the several parts is made higher than that produced at the throat of the vacuum Venturi tube 25.

As the throttle 12 is opened to speed up the engine, and as the engine speed increases responsive thereto, the flow of air through the carburetor correspondingly increases. The static suction within the mixing chamber likewise increases, because it is controlled by the spring 9, which somewhat increases in pressure as it is collapsed. The velocity suction within the movable tube 10, however, increases very rapidly due to the very greatly increased flow of air, so that the quantity of fuel drawn in is substantially proportional to the quantity of air, thus maintaining a substantially constant mixture. This mixture, however, may be accurately adjusted by the contour of the outer wall of the movable tube 10 at the position 26 so as to vary the amount of air entering through the Venturi tube 25, and thus to create slight alterations in the float chamber suction to bring about the correct mixture. The shape of the contoured portion of the movable tube 10 is experimentally determined, and once having been determined will be the same in all carburetors of like capacity.

The degree of richness of the mixture may be controlled, for example, for summer and winter driving, or for starting by rotating the cam 30 so as to change the degree of restriction at the entrance to the Venturi tube 25. When the cam is rotated so as to entirely close this entrance, the mixture will be very greatly enriched, because under this condition the float chamber receives only the same vacuum as the mixing chamber. As the cam is moved to enlarge the entrance opening to the Venturi tube 25, the effectiveness of the Venturi tube 25 increases, and the vacuum in the float chamber correspondingly increases, thus decreasing the fuel feeding differential between the float chamber pressure and that at the throat of the nozzle Venturi tube 15, thus leaning the mixture.

Although I have shown and described my invention with respect to certain details illustrated in the drawing, it is to be understood that variations may be made without departing from the spirit or scope of the invention.

I claim:

1. In a carburetor for internal combustion engines, the combination of a cylindrical induction passage, a sleeve arranged to reciprocate longitudinally within said passage, an abutment against which the anterior open end of said sleeve normally rests to close communication between atmosphere and the interior of said induction passage, said sleeve having an enlargement fitting the passage, one surface of said enlargement being subjected to atmospheric pressure whereby suction in the induction passage tends to raise

- 5 said sleeve off of the abutment, a spring for normally holding said sleeve against the abutment, a nozzle Venturi tube projecting through the abutment and having its delivery end projecting somewhat beyond the plane at which said sleeve strikes said abutment, fuel delivery means in said nozzle Venturi tube, a fuel chamber communicating with said means, a vacuum Venturi tube 10 extending through the wall of the induction passage and having its delivery end positioned opposite a portion of said sleeve, a duct for connecting the throat of said vacuum Venturi tube with the upper space of 15 the fuel reservoir for creating a suction therein for lifting fuel thereto, the said sleeve having a contoured outer surface for variably regulating the amount of air drawn in through said vacuum Venturi tube.

20 2. In a carburetor, the combination with a casing, a chamber therein for connection with the intake of an induction motor, a nozzle Venturi tube having one end exposed to atmosphere, and the other end extending into 25 said chamber, an enlargement about the end of said Venturi tube, an atmospheric communication surrounding said enlargement, a sleeve operating in said chamber and having an end which abuts upon said enlargement 30 to close a communication between atmosphere and said chamber, said sleeve being movable out of contact with said enlargement under the influence of suction in said chamber, the air passing into said chamber 35 between said enlargement and the end of said sleeve being directed past the end of said Venturi tube for creating an additional suction on said Venturi tube, a fuel reservoir, a vacuum producing Venturi tube extending 40 from atmosphere into said chamber, and a connection between said Venturi tube and the upper part of said fuel reservoir controlled by movement of said sleeve for creating a suction therein for lifting fuel thereto.

45 3. In a carburetor, the combination with a casing, a chamber therein for connection with the intake of an induction motor, a nozzle Venturi tube having one end exposed to atmosphere, and the other end extending into said chamber, an enlargement about the end of said Venturi tube; an atmospheric communication surrounding said enlargement, a sleeve operating in said chamber and having an end which co-operates with said enlargement to close a communication between atmosphere and said chamber, said sleeve being movable out of contact with said enlargement under the influence of suction in said chamber, the air passing into 50 said chamber between said enlargement and the end of said sleeve being directed past the end of said Venturi tube for creating an additional suction on said Venturi tube, a fuel reservoir effectively closed to atmosphere, a vacuum producing Venturi tube extending 55 from atmosphere and discharging into said chamber, a connection from said Venturi tube to said fuel reservoir for creating a suction therein for lifting fuel thereto, the inner end of said vacuum producing Venturi tube terminating in the region of the external surface of said sleeve, said sleeve being contoured to control the discharge of air from the inner end of said Venturi tube, whereby the suction in the fuel reservoir 60 may be controlled.

65 In witness whereof, I hereunto subscribe my name this 3rd day of October, 1922.
